UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A BRUSH OR MIRROR BACK.

SPECIFICATION forming part of Design No. 18,943, dated March 5, 1889.

Application filed January 14, 1889. Serial No. 206,296. Term of patent 7 years.

To all whom it may concern:

Be it known that I, HENRY BERRY, a citizen of the United States, residing at Shelton, in the county of Fairfield and State of Connecticut, have invented and produced a certain new and original Design for a Brush or Mirror Back, of which the following is a specification, reference being had to the accompanying drawing, which forms a part thereof, and which shows a plan view of a mirror or brush back shaped in conformity with my design.

The leading features of my design consist in the peculiar shape or outline of the backing which contains the brush or glass and in the shape or outline of the handle which is attached thereto.

As is the backing, which is enlarged and bulging in outline at its rear end, as seen at *a*, but which narrows to a gracefully-rounded point, *b*, at its outer end. One side or edge of the backing *c* is conformed to a substantially regular curve. The other side or edge is slightly sinuous in outline, as seen at *d*. A conventional leaf design, *e*, appears upon the backing at the large end thereof and joins the handle *B* thereto. The handle *B* is enlarged near its upper end, as at *f*, and thence tapers and

curves gently downward, ending in a horn-shaped extremity, *g*. Upon the handle appear flutings *h*, which follow the curves of the handle, and the representation of a folded leaf-shaped cap appears as inclosing the horn-shaped end. This detail ornamentation is, however, not the leading feature of my design, which, as heretofore stated, principally resides in the outline of the back and of the handle.

I claim—

The design for brush-backs or the like, the same comprising the backing enlarged and bulging in outline at its rear end and tapering to a rounded and curved point at its outer end, one edge thereof being continuously curved and the other sinuously curved, and having the handle joining the back at the center of the large end thereof, substantially as shown and described.

In testimony whereof I affix my signature in presence of two witnesses.

HENRY BERRY.
